Attorney.

UNITED STATES PATENT OFFICE.

HENRY LANGE, OF QUINCY, ILLINOIS.

STOVE HINGE.

Application filed January 21, 1924. Serial No. 697,606.

To all whom it may concern:

Be it known that I, HENRY LANGE, a citizen of United States, residing at Quincy, in the county of Adams and State of Illinois, have invented certain new and useful Improvements in Stove Hinges, of which the following is a specification, reference being had therein to the accompanying drawing.

The present invention relates to hinges for stove doors, and aims to provide novel and improved hinges of that kind, whereby the construction is neat and plain in appearance, and also eliminates obstructions on the exterior of the stove which are not only unsightly but which also catch dirt and become unsanitary.

Another object of the invention is the provision of such a hinge construction wherein the portions of the hinges which are exposed to view are integral with the wall of the stove, to enhance neatness and avoid separate pieces or obstructions fastened to the wall on the exterior.

A further object is the provision of such a construction wherein one hinge pintle of the door is seated against the stove wall or door frame from the inside, in assembling the door with the wall or frame, with the retaining member for said pintle at the inner side of said wall or frame and concealed from view.

A still further object of the invention is the provision of a spring for the hinge which is also concealed from view behind the stove wall or door frame.

It is also an object of the invention to provide a hinge construction of the character indicated which is simple and economical in construction and manufacture.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a side elevation showing the outer side of a stove wall having two doors, such as used in a coal or gas stove or range.

Fig. 2 is a fragmentary elevation of said wall and doors showing the inner or back surfaces thereof.

Fig. 3 is a view similar to Fig. 2, with

portion of the retainer plate broken away to expose the corresponding hinge pintle and spring of one door.

Fig. 4 is a horizontal section on the line 4—4 of Fig. 3.

Fig. 5 is a vertical section on the line 5—5 of Fig. 2 with the corresponding door swung open.

The numeral 10 designates the front or side wall of a stove or range, which is usually of cast metal, and which, as shown, has the two door openings 11 for which the doors 12 are provided. The doors 12 are preferably flush with the outer surface of the wall 10 when the doors are closed, and the doors open outwardly as usual.

The hinge mounting for each door is the same, and the only connection between the two doors resides in the use of a common retainer plate 13, as will hereinafter more fully appear.

Each door 12 is provided with the hinge pintles 14 and 15 at the corresponding lower and upper corners of the door at one vertical edge of the door, and said pintles are shown as being located at the left hand edges of the doors, although they can be at the right hand edges, for either left hand or right hand doors. The pintles 14 are offset from the corresponding vertical edge of the door in the plane of the door, as shown, and the lower pintle 14 extends downwardly while the upper pintle 15 extends upwardly to engage the hinge portions of the wall or frame.

The wall or frame 10 is formed at the corresponding lower corner of each door opening 11 with an outwardly bulged portion 16 having an aperture 17 in the top thereof for receiving the pintle 14 when moving the pintle downwardly into said aperture, thereby providing the hinge connection between the lower corner of the door and the wall or frame.

The wall or frame 10 is provided at the corresponding upper corners of the door openings 11 with outwardly bulged portions 18 for the engagement of the upper pintles 15, but such pintles 15, instead of being inserted longitudinally into engagement with the portions 18, similar to the engagement of the pintles 14 with the portions 16, are moved transversely from behind said portions 18 into engagement with said portions. The bottoms of the portions 18 have notches 19 in which the pintles 15 seat behind or

at the inner side of the wall or frame 10, and the wall 10 is open, as at 20, in rear of each bulged hinge portion 18, for the passage of the pintle 15 and corresponding upper corner portion of the door.

Each door can be readily assembled with the wall 10, with the door in partially open position, by inserting the pintle 14 into the aperture 17 of the hinge portion 16, and tilting the hinge edge of the door inwardly so that the pintle 15 is moved under the upper edge of the door opening 11, and behind the wall or frame 10. Then, by swinging the door into position, to bring the hinge edge thereof vertical, the pintle 15 and corresponding corner portion of the door can move through the opening 20 to seat the pintle 15 in the notch 19 of the hinge portion 18, and the door can then be swung closed. The hinge pintles 15 of the doors are thus seated against the portions 18 of the wall or frame 10 from the inner or rear side, and from the exterior the pintles 15 have the appearance of being inserted in apertures of the portions 18 similar to the insertion of the pintles 14 into the portions 16. The only portions of the hinges showing on the exterior are the butt ends of the pintles 14 and 15 and the bulged portions 16 and 18 of the wall or frame 10. This provides a neat and plain appearance, without objectionable obstructions in or on which dirt will lodge or accumulate, and dust settling on the portions 16 and 18 can be readily brushed or wiped off.

The retainer plate or strip 13 extends along the upper edge portion of the wall 10 across both pintles 15, a single plate thus being used for both hinges, and said plate 13 is secured to the wall 10 by bolts 21 or other suitable securing elements. Said plate closes the openings 20, being formed to fit the wall 10 and in the openings 20 behind the pintles 15, and the portions 22 of the plate 13 which fit in the openings 20 form a part of the flanges or stops 23 surrounding the openings 11, against which the doors 12 bear when closed. This will prevent a broken appearance of the edges of the door openings where the openings 20 occur.

The pintles 15 have lugs 24 seating on the bottoms of the portions 18, to support or suspend the doors for free swinging motion, with the lower edges of the doors spaced above the portions of the wall 10 under said doors when the doors are closed. The lower edges of the doors, therefore, do not seat on the wall or frame 10 when the doors are closed, and when the pintles 15 are moved into the portions 18, the lugs 24 are brought over the bottoms of said portions 18 to thereby support or suspend the doors from the upper pintles 15.

Springs are provided for the doors, and as shown, leaf springs 25 are used, being

disposed between the plate 13 and wall 10. Said springs 25 are secured to the wall 10 by screws 26 or other securing elements, at the sides of the corresponding bulged portions 18, and said springs extend across and bear against the pintles 15. Said pintles have the cams 27, opposite to the lugs 24, so that when the doors are opened, the cams 27 will force the springs 25 inwardly, and if the doors are only slightly opened, the springs exerting pressure against the cams 27, will swing the doors closed. However, by swinging the doors fully open, or at right angles with the wall 10, the cams 27 are brought to substantially right angles with the springs 25, so that the doors will remain open, the springs in engaging frictionally under pressure with the cams 27 serving to prevent accidental swinging movement of the doors from such open position. The plate 13 has openings 28 behind the springs 25 to permit the springs to flex rearwardly or inwardly.

The present hinge construction presents no broken lines or surfaces at the exterior, where exposed to view, and the surfaces of the structure at the hinges are smooth and plain, so as not only to be neat and attractive in appearance, but to also prevent the accumulation of dirt. The wall or frame 10 also has a solid appearance.

Having thus described the invention, what is claimed as new is:—

1. A structure of the character described comprising a wall having a hinge portion and an opening behind said hinge portion, an outwardly opening door at the outer side of said wall having a pintle inserted from the inner side of said wall outwardly through said opening into said hinge portion, and means for retaining said pintle in said hinge portion.

2. A structure of the character described comprising a wall having a door opening, a hinge portion, and an opening extending from behind said portion to the door opening, and an outwardly opening door for said wall to close the door opening and having a pintle moved outwardly from the inner side of said wall through the second named opening and seated outwardly in said hinge portion.

3. A structure of the character described comprising a wall having a door opening, a hinge portion, and an opening extending from behind said portion to the door opening, an outwardly opening door for said wall to close the door opening and having a pintle moved outwardly from the inner side of said wall through the second named opening and seated outwardly in said hinge portion, and means behind said hinge portion and pintle for retaining the pintle in said portion.

4. A structure of the character described

comprising a wall having an outwardly bulged hinge portion formed with an inwardly opening notch, said wall having an opening behind said portion, and an outwardly opening door for said wall having a pintle moved outwardly from the inner side of said wall through said opening and seated outwardly in said notch.

5. A structure of the character described comprising a wall having a door opening and an outwardly bulged hinged portion formed with a rearwardly opening notch, said wall having an opening extending from behind said portion to the door opening, an outwardly opening door for said wall having a pintle moved outwardly from the inner side of said wall through the second-named opening and seated outwardly in said notch, and means for retaining said pintle 20 in said notch.

6. A structure of the character described comprising a wall having a hinge portion, an outwardly opening door for said wall having a pintle seated in said portion from the inner side of the wall and extending behind said portion, and a retainer member secured to said wall behind said portion and pintle.

7. A structure of the character described comprising a wall having an outwardly bulged hinge portion formed with a notch, an outwardly opening door for said wall having a pintle seated in said notch from the inner side of said wall and extending behind said portion, the wall having an opening behind said portion for the passage of said pintle into and out of the notch, and a retainer plate secured to said wall behind said portion and having a portion fitting in and normally closing said opening.

8. A structure of the character described comprising a wall having a hinge portion, an outwardly opening door for said wall having a pintle seated in said portion from the inner side of the wall and extending behind said portion, a retainer member secured to said wall behind said portion, and a spring secured between said wall and member and bearing against said pintle.

50 9. A structure of the character described comprising a wall having an outwardly bulged hinged portion formed with a notch, an outwardly opening door for said wall having a pintle seated in said notch from the inner side of said wall and extending behind said portion, a retainer plate secured to said wall behind said portion, and a leaf spring secured between said wall and bearing against said pintle, the pintle having a cam for bending the spring inwardly when the door is opened.

10. A structure of the character described comprising a wall and an outwardly opening door for said wall, said wall having hinge portions and the door having op-

positely extending pintles engaging said portions and extending behind same, one of said pintles having a lug engaging the corresponding portion to suspend the door from said lug.

70

11. A structure of the character described comprising a wall having outwardly bulged hinge portions, and a door for said wall having oppositely extending pintles engaging in and extending behind said portions, one pintle having a lug within the corresponding portion and seating on said portion to suspend the door from said lug.

75

12. A structure of the character described comprising a wall having hinge portions, and an outwardly swinging door for said wall having pintles, one inserted lengthwise into one of said hinge portions and the other seated transversely from the inner side of said wall in the other hinge portion behind said portion, the second-named pintle having a lug to seat on the second named hinge portion for suspending the door from said lug.

80

13. A structure of the character described comprising a wall having outwardly bulged hinge portions, one of said portions having an aperture and the other having a notch at the inner side of said wall, and an outwardly swinging door for said wall having pintles, one inserted longitudinally into said aperture and the other seated from the inner side of said wall in said notch, the last named pintle having a lug seating from the corresponding hinge portion within said portion above said notch for suspending the door from said lug.

95

14. A structure of the character described comprising a wall having lower and upper hinge portions, a door opening outwardly and having a lower downwardly extending pintle and an upper upwardly extending pintle, the lower pintle pivotally engaging the lower hinge portion, the upper hinge portion having a rear notch and the upper pintle being seated in said notch from the inner side of said wall, the upper pintle having a lug seating in the upper hinge portion to suspend the door from said lug, and means carried by said wall in rear of the upper pintle to hold it seated in said notch.

105

15. A structure of the character described comprising a wall having lower and upper hinge portions, a door opening outwardly and having a lower downwardly extending pintle and an upper upwardly extending pintle, the lower pintle pivotally engaging the lower hinge portion, the upper hinge portion having a rear notch and the upper pintle being seated in said notch from the inner side of said wall, the upper pintle having a lug seating in the upper hinge portion to suspend the door from said lug, and a leaf spring secured to said wall and extending 125

120

125

130

behind the upper pintle, said upper pintle having a cam to bend the spring inwardly when the door is opened.

16. A structure of the character described comprising a wall having lower and upper hinge portions, a door opening outwardly and having a lower downwardly extending pintle and an upper upwardly extending pintle, the lower pintle pivotally engaging the lower hinge portion, the upper hinge portion having a rear notch and the upper pintle being seated in said notch from the inner side of said wall, the upper pintle having a lug seating in the upper hinge portion to suspend the door from said lug, the wall having an opening in rear of said upper portion for the passage of the upper pintle, a retainer plate secured to said wall behind said upper portion and having a por-

tion disposed in and normally closing said opening, and a leaf spring secured between said wall and plate and extending behind the upper pintle, said upper pintle having a cam for bending the spring inwardly when the door is opened.

17. A structure of the character described comprising a wall having a hinge portion and an opening behind said hinge portion, an outwardly opening door for said wall having a pintle seated in said portion from the inner side of said wall and extending behind said portion, and a retainer plate secured to said wall behind said portion and having a portion disposed in and normally closing said opening.

In testimony whereof I hereunto affix my signature.

HENRY LANGE.
